UNITED STATES PATENT OFFICE

GUILLAUME DUCART, OF PARIS, FRANCE

GAS-OPERATED AIR-HEATING DEVICE

Application filed May 31, 1927, Serial No. 195,520, and in France June 4, 1926.

The present invention relates to a gas operated air heater more particularly adapted for use as an air dryer for hairdressing appliances and the like. It has been recognized that the apparatus at present in use and heated by gas presents serious disadvantages on account of the fact that the air to be heated is in direct contact with the heating gas for which it serves as burning agent, a consequence of which is that the air which is employed for drying is not pure but is mixed with burnt gas, which vitiates the atmosphere of the rooms in which these appliances are employed and makes it practically impossible to use a large number of pieces of apparatus in the same room. This disadvantage is further accentuated by the fact that the circulation of the air is obtained by means of a suction or pressure fan and that, as a consequence of the speed of the air to be dried, the gas is burned under unfavourable conditions and a part of the gas is carried along by the air without being burned.

The object of the present invention is to remove the above mentioned drawbacks existing in a present day apparatus of this type and with this object in view it has for its object a gas operated air heater characterized by the feature that the air is heated without being placed at any moment in contact with the burning gases, a fact which presents the advantage of giving a supply of absolutely pure hot air. The apparatus further comprises certain constructional features which are described hereinafter and which permit a construction to be made which is simple and cheap.

This gas operated air heater forming the subject of the invention is hereinafter described in detail with reference to the accompanying drawings in which:

Fig. 1 is a front elevation of the apparatus.

Fig. 2 is a side elevation.

Fig. 3 is a longitudinal section taken along the line $x-x$ in Fig. 4.

Fig. 4 is a cross section along the line $y-y$ in Fig. 3 and

Fig. 5 is a cross section taken along the line $z-z$ in Fig. 3.

In these figures 1 represents two elements

or shells which by being joined or combined with a casing or cover 2 make it possible to construct in a simple manner ducts or channels for the air to be heated on the one hand, and for the hot burnt gases on the other, without these fluids becoming mixed with each other. For this purpose each shell 1 comprises internal walls or fins 3 and also external walls or fins 4 preferably formed on the shells by casting. By joining together two shells 1, the fins 3 being placed end to end, there is obtained an internal partition arrangement forming ducts 5 for the circulation of the air to be heated which is admitted into the apparatus from a fresh air pipe through an inlet nozzle 6 and is discharged through an outlet nozzle 7 into a hot air duct or directly into the consuming device, the arrows a indicating the direction of flow of the air to be heated.

The shells 1, thus joined together may be united by any suitable means, holes being provided for example for taking bolts. The whole arrangement is enclosed by the casing or cover 2 with the interposition between the said casing and the shell 1 of sheets of asbestos or other heat resisting body, the outer fins 4 then bounding the ducts 10 for the hot burnt gases the heat from which is conveyed to the air to be heated by conduction through the walls of the shells 1.

The lighting gas or other gasified fuel is led into the heating burners 11 which are two in number each disposed outside of one of the shells 1, to which burners it is led through tubes 12 and 13, the delivery being regulated by a thermo-regulator apparatus or thermostat 14 which is fed with gas through a pipe 15 and the function of which, when a predetermined temperature has been reached, is to cut off the normal supply of gas and leave only a pilot jet ignited with a view to maintaining this temperature. This apparatus may be of any suitable type but will preferably be of the type described in my copending application Ser. No. 195,519, filed of even date; this type of thermostat essentially comprises a thermometric member lodged in a casing and having a lower co-efficient of expansion than the latter, this

difference in capacity, for expansion being employed to make the thermometric member actuate a valve controlling the admission of gas.

5 In order to house a thermometrical member and its casing of the construction shown in my copending application herein referred to, there are provided in adjacent faces of each of the shells 1 vertical grooves of semi-circular cross section 16 and 16' so that when 10 the two shells are arranged together two circular channels 17 and 17' are formed, only one of which is utilized at a time for accommodating the tube 21 and the rod 22. Accordingly as the temperature of the shells 1 increases the tube 21 expands while the thermometrical rod 22 expands at the same time. The expansion of the rod is much less than 15 that of the tube 21 and moreover being subjected to the action of the spring, not shown, it tends to bear constantly against the base of the tube 21 it follows the displacements of the tube 21 and these displacements are utilized for regulating and checking the arrival 20 of the gas in the burners 11 as clearly described in my co-pending application 195-519 filed May 31, 1927. The air for the combustion of the gas is led to the burners 11 through perforations 18 in the casing 2 and 25 also through windows 19 formed in the casing 2 and through which the air enters as indicated by the arrows *b*. The burnt gases pass along the ducts 10 and after heating the air in the ducts 5 are discharged through 30 holes 20 without becoming mixed with the hot air.

35 It is to be clearly understood that it is possible, without going outside the scope of the invention, to make modifications and improvement in details; for example it is possible, by a judicious arrangement of suitable elements, to make the air pass through baffles in the interior of the apparatus.

40 What I claim is:

45 1. An air heater of the character described, including a casing, a pair of identical shells of a heat conducting material arranged within the casing and provided on their adjacent inner faces with spaced vertical fins which 50 when the shells are arranged together provide a series of vertical and parallel passages for air to be heated, said shells also provided on their outer surfaces with a series of vertical fins which coact with the inner 55 surfaces of the side walls of the casing to form passages through which heated gas may be passed, the ends of the shells being extended beyond the fins and projected through the ends of the casing and forming inlet and 60 outlet air connections, and gas burners arranged in the lower part of the casing beneath the fins on the outer surfaces of the shells.

65 2. A device as claimed in claim 1, wherein the casing is provided adjacent the lower

and upper ends with apertures for facilitating the combustion of the gases when the burners are ignited and for allowing the spent gases to pass from the casing.

3. A device as claimed in claim 1, wherein 70 the casing is provided adjacent the lower and upper ends with apertures for facilitating the combustion of the gases when the burners are ignited and for allowing the spent gases to pass from the casing, and windows provided 75 on the outer side walls and adjacent the lower ends of the casing and the burners.

4. A device as claimed in claim 1, wherein 80 the adjacent faces of the shells are provided with grooves which when the shells are secured together form passages one of which is adapted to receive a thermometrical element.

85 In testimony whereof I affix my signature.

GUILLAUME DUCART.
